RAILWAY TRAFFIC CONTROLLING APPARATUS

Application filed September 23, 1929. Serial No. 394,402.

This invention relates to railway traffic controlling apparatus, and particularly to apparatus for controlling traffic in both directions over a single stretch of track.

5 One purpose of the invention is the provision of novel means for establishing the direction of traffic within a single track section independently of traffic conditions in any other track section. The invention further comprises the provision of means for selectively bringing into action different devices in accordance with the direction of traffic, said means comprising relays having different releasing characteristics.

10 15 We shall describe one form of apparatus embodying our invention and shall then point out the novel features thereof in claims.

The accompanying drawing consists of a 20 diagrammatic view illustrative of our invention.

Referring to the drawing, the numeral 5 designates a section of railway track. This section is provided with a track relay 6 having one winding 6' connected across the rails adjacent one end of the section and having a second winding 6'' constantly supplied with alternating current from terminals B and C of a source of energy not shown in the 25 drawing. A track transformer 7 has its secondary connected across the rails adjacent the opposite ends of the section, and the primary 7' of the transformer is at times connected with terminals B and C as will 30 be described in detail hereinafter. A floating relay 8 has its winding 8' connected to the leads of transformer 7, and winding 8'' of this relay is connected with terminals B and C. Relays 6 and 8 have different releasing characteristics; the relay 6 being designed to release its contacts comparatively slowly in response to de-energization of its winding 6', and the relay 8 releasing its contacts comparatively quickly when its winding 8' is de-energized. Relays possessing 35 such releasing characteristics are well known in the art and need not be specifically described. We utilize the difference in releasing characteristics of said relays for selectively bringing into action different de-

vices in accordance with the direction of movement of traffic in the track section 5. In this connection we have shown relays 9, 10, respectively, at the right hand end of the track section and other relays, 11, 12 55 respectively, at the opposite end; and through our invention we are enabled to selectively energize certain of said relays (9 and 12, for example) in response to the travel of traffic in one direction in the track 60 section 5 and to selectively energize others of said relays (10 and 11, for example) in response to traffic movement in said section in the opposite direction.

When a train enters the track section 65 from the right it de-energizes the relay 6. The floating relay 8 is not de-energized, however, until the train has reached some intermediate point in the section. While upon de-energization of relay 6 its armature 70 will not drop instantaneously into engagement with back contact 14 said armature will make such engagement before the train has arrived at such point in the section as to de-energize the relay 8. Upon engagement 75 of armature 13 with said contact 14 and while armature 15 if relay 8 remains in engagement with front contact 16, a circuit is completed from terminal B through wire 17, back contact 18 and armature 19 80 of relay 9, wire 20, contact element 21 operable by the switch 22 and engaged with contact 23 when said switch is in normal position, contact 23, wire 23', back contact 14 and armature 13 of relay 6, wire 24, armature 15 and front contact 16 of relay 8, wire 25, back contact 26 and armature 27 of relay 12, wire 28, relay 11, wire 29, relay 10, and wire 30 to terminal C. The relays 10 and 11 are thereby energized. As soon as the 85 train has advanced a sufficient distance into the track section, the relay 8 opens, and its armature 15 is disengaged from contact 16, but the relays 10, and 11 remain energized by way of a stick circuit comprising wire 31 connected to wire 24, armature 32 and front contact 33 of relay 11, and wire 34 connected to wire 28; said stick circuit being closed upon the energization of relay 11 aforesaid. It will be apparent that the 90 95 100

relays 10 and 11 are de-energized and that the apparatus is restored to its normal condition upon energization of relay 6 when the train leaves the track section.

- 5 If a train enters section 5 from the left relays 6 and 8 both become de-energized, but due to the slow releasing characteristics of relay 6, relay 8 releases before relay 6 releases. Relays 10 and 11 will remain de-
10 energized because the armature 15 of relay 8 will move out of engagement with front contact 16 before armature 13 of relay 6 engages back contact 14. Said train will, however, cause the relays 9 and 12 to be
15 energized; since upon de-energization of relay 8 and engagement of its armature with back contact 35 while armature 13 of relay 6 engages front contact 36 a pick-up circuit for relays 9 and 12 is closed from terminal
20 B, through wire 37, armature 38 and back contact 38' of relay 11, wire 39, back contact 35 and armature 15 of relay 8, wire 24, armature 13 and front contact 36 of relay 6, wire 40, wire 41, back contact 42 and armature 43 of relay 10, wire 44, relay 9, wire 45, contact 46, contact element 47 operated by switch 48 and engaged with contact 46 when said switch is in normal position, wire 49, relay 12, and wire 50 to terminal C. Relays 9 and 12 therefore become energized
25 in series. At the expiration of the holding time of relay 6, this relay releases, interrupting the circuit just traced, but current continues flowing through said relays 9 and
30 12 by way of a stick circuit comprising wire 51 connected to wire 24, armature 52 and front contact 53 of relay 9, and wire 54 connected to wire 40, said stick-circuit being established upon energization of said relay
35 9. Also, in response to de-energization of the relay 6 the armature 55 thereof engages back contact 56 and establishes a second stick circuit, from battery through said armature 55 and back contact 56, wire 57, armature 58 and front contact 59 of relay 9, and wire 60 to wire 40, so that relays 9 and 12 will remain energized when the train has proceeded far enough into the track section to allow relay 8 to become energized.
40 Current then flows from terminal B through armature 55, back contact 56, wire 57, armature 58, front contact 59, wire 60, wire 40, wire 41, back contact 42 and armature 43, wire 44, relay 9, wire 45, contacts 46 and 47, wire 49, relay 12, and wire 50 to terminal C. The relays 9 and 12 are de-energized and the circuits restored to normal upon energization of relay 6 when the train leaves the track section. A train entering said section
45 from the right cannot energize the relays 9 and 12, because armature 13 of relay 6 is disengaged from front contact 36 before armature 15 engages back contact 35.

It will thus be seen that we have provided
50 for energizing different relays selectively

and automatically in accordance with the direction in which traffic moves in the track section 5. In other words, the direction of traffic in said section is set up by the energization of corresponding relays, and we have provided for such setting up of the direction of traffic independently of traffic movements in other track sections. Relays 9, 10, 11, and 12, being responsive to the direction of movement of traffic, may be termed directional relays. The number of directional relays employed may of course be varied as desired. For example, the relay 10 of the pair of relays responsive to movement of traffic to the left may be omitted and wire 29 connected directly to terminal C. Similarly, relay 12 of the pair responsive to traffic movements to the right may be omitted and wire 49 connected directly to terminal C.

We have shown wire 17 of the energizing circuit for relays 10 and 11 connected to wire 20 through back contact 18 and armature 19 of relay 9; while wire 25 of said circuit is shown connected to wire 28 through back contact 27 and armature 26 of relay 12. In this way a check is provided against any possibility of energization of relays 10 and 11 while either relay 9 or 12 is energized. Likewise a check against the possibility of energizing relays 9 and 12 while either relay 10 or relay 11 is energized is provided by connecting wire 41 to wire 44 through back contact 42 and armature 43 of relay 10 and by connecting wire 37 to wire 39 through armature 38 and back contact 38' of relay 11.

The relays energized in accordance with the direction of traffic in the track section 5 may be utilized in any suitable way to govern traffic within said section. One way in which said directional relays may be caused to control traffic is illustrated by way of example in the accompanying drawing, wherein the relay 11 is shown controlling a motor coder 65 for supplying coded train control energy to the rails adjacent the left hand end of the track section 5 while the relay 9 controls a motor coder 66 for supplying coded impulses to the rails adjacent the right hand end of said section. Each of said motor coders as is well known in the art, comprises an electric motor and means such as make and break cams driven thereby for causing the opening and closing of contacts at different frequencies. Thus, the contact element 67 is driven by motor coder 65 to engage contact 68 a given number of times per minute (180 for example) while contact element 69 is operable by said motor coder to engage contact 70 at a different rate (as, for example, 80 times per minute). Contact element 71 is operated by motor coder 66 to engage alternately the contacts 72, 73, each of said contacts being engaged,

for example, 180 times per minute by said element 71; while contact element 74 is operated by said motor coder 66 to engage contacts 75, 76 alternately and at a different rate (80 per minute, for example) than that at which contacts 72, 73 are engaged by contact element 71.

Assuming a train to enter the track section 5 from the left, relays 9 and 12 are energized as previously described, and the energization of relay 9 closes a circuit through the motor coder 66 as follows; from terminal B through wire 77, armature 78 and front contact 79 of said relay 9, wire 80, motor coder 66 and wire 81 to terminal C. Each of the contact elements 71, 75 of said motor coder is connected to a corresponding contact 82, 83 with which contacts there cooperates an armature 84 of a relay 85 responsive to traffic conditions to the right of section 5. Since connections for rendering said relay responsive to said traffic conditions are well known they will not be here described, and it is sufficient to note that the relay 85 is energized when traffic conditions to the right of section 5 are safe and is de-energized when said conditions are unsafe. If, at the time relay 9 is energized, relay 85 is also energized, current will flow from terminal B through wire 86, contact 72, motor coder contact 71 (each time that said contact engages contact 72), front contact 82 and armature 84 of relay 85, wire 87, back contact 88 and armature 89 of relay 10, wire 90, front contact 91 and armature 92 of relay 9, back contact 94 and armature 95 of track relay 6, wire 96 and primary 97' of a code feeding transformer 97 to terminal C. The secondary of transformer 97 is connected across the rails adjacent relay 6, and it follows that impulses of a frequency corresponding to the rate of engagement of contact element 71 with contact 72 are thus supplied to the rails adjacent the right hand end of section 5.

Connected in series with the coil 6' of track relay 6 is the primary winding 98' of an impedance transformer 98, the secondary winding 98'' of which is connected by wire 99 to motor coder contacts 73 and 76 so that upon engagement of contact 73 by contact element 71 when armature 84 of relay 85 is engaged with front contact 82, said secondary winding 98'' is short circuited, and likewise when armature 84 engages back contact 83, said secondary is short circuited each time that contact element 74 engages contact 76. It may be noted that each time that a circuit is closed by contacts 71, 72 through the winding 97' of transformer 97, the secondary winding 98'' of transformer 98 is open-circuited since contact element 71 is at that time out of engagement with contact 73. The imped-

ance of the primary 98' of transformer 98 is thereby increased so that any substantial flow of current through track relay winding 6' is prevented and said track relay remains inactive.

If, at the time relay 9 is energized, the relay 85 is de-energized, current is supplied by the motor coder to transformer 97 by way of contact 75, contact element 74, and back contact 83 and armature 84 of relay 85, whereby there are applied to the rails at the right hand end of the track section impulses of a frequency corresponding to the rate of engagement of contact element 74 with contact 75. Each time that current is supplied to transformer 97 by contacts 74, 75 the secondary of transformer 98 is open-circuited, contact element 74 being at that time out of engagement with contact 76, and the impedance of transformer winding 98' is increased as aforesaid to prevent a flow of current through track relay winding 6' sufficient to bring said relay into action.

It will thus be seen that the energization of relay 9 may be utilized to cause impulses of coded energy to be supplied to the rails at the right hand end of the track section 5 in accordance with traffic conditions beyond said end of the section. Said impulses may be received by the usual apparatus on the front of the train and caused to give corresponding signals in the locomotive cab as is well understood in the art. The train which has entered the track section 5 from the left is thus apprised of traffic conditions beyond the right hand end of said section.

When said train leaves the track section 5, the track relay 6 is energized in response to energy supplied to the rails by transformer 7 as soon as the secondary 98'' of transformer 98 is short circuited by the contacts of the motor coder 66; the impedance of the winding 98' in series with track relay coil 6' then being sufficiently reduced by the short circuiting of transformer winding 98'' to permit the energization of the track relay. When said track relay is energized its armature 13 is disengaged from back contact 14, thereby de-energizing those directional relays which were previously energized. Also, when the track relay is energized its armature 95 engages front contact 99' whereby transformer winding 98'' is maintained short circuited through a circuit which will be apparent from an inspection of the drawing.

Under normal conditions, that is, when section 5 is unoccupied, and also when the section is occupied by a train moving from left to right, current is supplied to the primary winding 7' of transformer 7, from terminal B through back contact 101 and armature 102 of relay 11, and thence through wire 103 and primary 7' of transformer 7 to terminal C. When a train enters the track 130

section from the right and thereby causes the directional relays 10, 11 to be energized, armature 102 is disengaged from back contact 101 and is engaged with front contact 104 of the relay 11. The primary 7' of transformer 7 is now connected to battery through the contacts of motor coder 65; the circuit being from terminal B through either contacts 68-67 or contacts 70-69 of the motor coder (depending upon whether armature 105 of relay 106 engages front contact 107 or back contact 108), thence through wire 109, back contact 110 and armature 111 of relay 12, wire 113, front contact 104 and armature 102 of relay 11, wire 103, and transformer winding 7' to terminal C. The relay 106 is responsive to traffic conditions to the left of track section 5; the connections for rendering said relay so responsive being well understood in the art, and it being sufficient to note that said relay is energized when said traffic conditions are safe and is de-energized when said conditions are unsafe. Thus, the energization of directional relay 11 causes impulses of coded energy to be applied by transformer 7 to the rails adjacent the left hand end of section 5, the frequency of said impulses depending upon whether current is supplied through contact 67 or contact 69 of the motor coder, which in turn is determined by the position of the armature of relay 106. A train entering the track section 5 from the right is thus supplied with coded energy indicative of the traffic conditions to the left of said track section. The energization of relay 11, in addition to connecting transformer 7 to the motor coder contacts, energizes said motor coder through the engagement of armature 114 of said relay with front contact 115 so that said motor coder is brought into action concurrently with the connection of the transformer 7 with one or the other of the sets of contacts controlled by the motor coder. In addition the energization of relay 11 breaks the circuit through coil 8' of the floating relay 8, this being accomplished by disengagement of armature 116 of said relay from back contact 117. Thus, the track relay 8 is prevented from being energized by coded impulses supplied to the rails from transformer 7. When the train which has entered the track section 5 from the right leaves said section, the track relay 6 is energized by the first impulse of coded energy supplied to the rails by transformer 7 following the exit of said train; and thus the directional relays 10, 11 which were energized upon the entry of said train into the track section 5 are de-energized and the apparatus is restored to its normal condition.

The terms and expressions which we have employed are used as terms of description and not of limitation, and we have no in-

tention, in the use of such terms and expressions, of excluding any mechanical equivalents of the features shown and described or portions thereof, but recognize that various structural modifications are possible within the scope of the invention claimed. 70

What we claim is:

1. In combination, a section of railway track, devices corresponding respectively to directions of movement of traffic in said section and means comprising relays having different releasing characteristics for bringing one of said devices into action upon traffic movement in one direction in said section and for bringing another of said devices into action upon traffic movement in said section in the opposite direction. 75
2. In combination, a section of railway track, a relay corresponding to movement of traffic in one direction in said section, a relay corresponding to movement of traffic in another direction in said section, and means comprising other relays having different releasing characteristics for energizing one or the other of the first mentioned relays in accordance with the direction of traffic in said section. 85
3. In combination, a section of railway track, a relay having a relatively slow release characteristic connected to the rails adjacent one end of said section, a relay having a relatively rapid release characteristic connected to the rails adjacent the opposite end of said section, and means jointly controlled by said relays for setting up the direction of traffic in either of opposite directions in said section. 95
4. In combination, a section of railway track, a relay having a relatively slow release characteristic connected to the rails adjacent one end of the section, a relay having a relatively rapid release characteristic connected to the rails adjacent the opposite end of said section, devices corresponding respectively to directions of movement of traffic in said section, and means controlled by said relays for bringing one of said devices into action when traffic moves in said section in one direction and for bringing the other of said devices into action when traffic moves in the other direction in said section. 105
5. In combination, a section of railway track, a relay corresponding to movement of traffic in one direction in said section, a relay corresponding to movements of traffic in another direction in said section, means comprising other relays having different releasing characteristics and effective upon the entrance of a train into said section to energize a selected one of said first mentioned relays in accordance with the direction of movement of said train, and traffic controlling means controlled by the first mentioned relays. 115

6. In combination, a section of railway track, a normally energized track relay connected to the rails adjacent one end of said track section, a normally energized floating relay connected to the rails adjacent the other end of said section said track relay being released prior to said floating relay in response to travel of traffic in one direction in said section and being released subsequent to said floating relay in response to travel of traffic in the opposite direction in said section, a directional relay, means for bringing said directional relay into action in response to release of said track relay while the floating relay is closed, a second directional relay, and means for bringing said second directional relay into action in response to release of the floating relay while said track relay is closed.
7. In combination, a section of railway track, a normally energized track relay connected to the rails adjacent one end of the track section, a normally energized floating relay connected to the rails adjacent the other end of said section, said track relay being released prior to said floating relay in response to travel of traffic in one direction in said section and being released subsequent to said floating relay in response to travel of traffic in the opposite direction in said section, a directional relay, means for energizing said directional relay in response to release of said track relay while floating relay is closed, means for subsequently maintaining said directional relay energized until the track relay is again energized, a second directional relay, means for energizing said second directional relay in response to release of the floating relay while said track relay is closed, and means for subsequently maintaining said second directional relay energized until said track relay is again energized.
8. In combination, a section of railway track, a first directional relay, a second directional relay, means comprising other relays connected to the rails of said track section and having different releasing characteristics for energizing said first directional relay in response to traffic movements in one direction in said section and for energizing said second directional relay in response to traffic movements in the opposite direction in said section, and means for preventing energization of either of said directional relays when the other is energized.

In testimony whereof, we have signed our names to this specification this 20th day of September, 1929.

HOWARD A. THOMPSON.
CHARLES A. BROOKS.
